ABSTRACT

A section of relatively high impedance waveguide is connected via abrupt waveguide transitions at opposite ends thereof to second and third waveguides having substantially lower characteristic impedance. A gas-tight wave permeable window member is hermetically sealed across the center section of high impedance guide. The second waveguide has a substantially lower characteristic impedance than the third waveguide and the window member is displaced in the high impedance guide toward the low impedance guide to form a relatively broad band impedance match, thereby forming the composite window and waveguide transformer structure.

COMPOSITE MICROWAVE WINDOW AND WAVEGUIDE TRANSFORM

DESCRIPTION OF THE PRIOR ART

Heretofore, microwave windows having relatively broad bandwidth have been constructed wherein a half wavelength section of relatively high impedance waveguide was connected at opposite ends to second and third sections of waveguide of equal and lower characteristic impedance. A wave permeable window member was transversely sealed across the high impedance guide at a point substantially midway along the length thereof. Such a window is disclosed and claimed in U.S. Pat. No. 2,958,834 issued Nov. 1, 1960 and assigned to the same assignee as the present invention. This window has the advantage that it is capable of passing relatively high microwave power levels, as of 4 MW peak at S band, and relatively high average powers, as of 8 KW average, over a relatively wide band of frequencies, as of 15 to 30% with a VSWR less than 1.1.

This prior art window is typically used as the output window of a high power pulsed microwave tube, such as a klystron, traveling wave tube or magnetron. However, in such applications, the waveguide feeding outwardly of the microwave tube generally has a reduced height compared to normal waveguide to accommodate magnetic beam focusing structure and the like typically surrounding the tube. Also, the output waveguide normally has a reduced height in order to have a lower characteristic impedance for providing an improved waveguide match to the output load impedance of the tube.

Therefore, in the prior art, a multiple step waveguide transformer section was provided between the output of the microwave tube and the microwave window, such that the input side of the microwave window could be connected to standard height waveguide.

The problem with this arrangement is that such a waveguide transformer is generally relatively costly and it would be desirable to eliminate the separate transformer if possible.

SUMMARY OF THE PRESENT INVENTION

The principal object of the present invention is the provision of an improved composite microwave window and waveguide transformer.

One feature of the present invention is the provision of a composite microwave window and waveguide transformer wherein a first section of waveguide, which is approximately an integral number of half wavelengths long, having a microwave window member sealed thereacross is connected via abrupt waveguide transitions to second and third connecting waveguides at opposite ends thereof. One of the connecting waveguides is of lower characteristic impedance than the other and the window member is displaced from the mid-point in the first section of guide toward the low impedance connecting waveguide to provide a broad band impedance match to form a composite microwave window and transformer.

In another feature of the present invention, the first waveguide is of circular cross section and the second and third connecting waveguides are of rectangular cross section and the abrupt waveguide transitions include walls at opposite ends of the first waveguide section with rectangular apertures for providing wave en-

ergy communication between the second and third and first waveguide sections.

In another feature of the present invention, the low impedance rectangular connecting waveguide has a height of approximately $\frac{1}{3}$ of its width and the third waveguide is rectangular having a height which is approximately $\frac{1}{2}$ of its width.

Other features and advantages of the present invention will become apparent upon a perusal of the following specification taken in connection with the accompanying drawings, wherein:

BRIEF DESCRIPTION OF THE DRAWINGS

FIG. 1 is a perspective view, partially cut away, of a prior art window assembly,

FIG. 2 is a longitudinal cross sectional view, in schematic line diagram form, of the structure of FIG. 1 taken along line 2-2 in the direction of the arrows and modified to include a prior art waveguide transformer;

FIG. 3 is a longitudinal sectional view of a composite waveguide transformer and microwave window incorporating features of the present invention, and

FIG. 4 is a plot of voltage standing wave ratio v. frequency in GHz depicting the bandwidth characteristics of the composite window and transformer of the present invention.

DESCRIPTION OF THE PREFERRED EMBODIMENTS

Referring now to FIG. 1, there is shown the prior art microwave window 1. The window structure 1 includes a first section of hollow cylindrical waveguide 2 approximately an integral number of $\frac{1}{2}$ wavelengths long at the center frequency of the passband of the window 1. The cylindrical section of waveguide 2 is closed at opposite ends by centrally apertured end walls 3 and 4. Rectangular waveguides 5 and 6 of substantially lower height waveguide than the center cylindrical section 2 are connected to the center section 2 via the rectangular apertures 7 and 8 in opposite end walls 3 and 4. The apertures 7 and 8 are of the same dimensions as the inside dimensions of the rectangular waveguides 5 and 6, respectively. The centrally apertured end walls 3 and 4 provide abrupt waveguide transitions from the waveguides 5 and 6 to the central waveguide section 2.

A disc shaped wave permeable window member 9, as of alumina ceramic, is hermetically sealed, as by brazing, transversely across the central waveguide section 2 at a point substantially midway of its length. Such a prior art window provides a relatively broad band structure typically having a passband of approximately 20% and being capable of passing relatively high power, as of MW peak power and KW average power.

When the prior art window of FIG. 1 is employed as the output window in the typical microwave tube, it is desired to utilize a waveguide transformer for connecting the normal height waveguide 5 to the output waveguide of the microwave tube. The output waveguide of the microwave tube is shown at 11 in FIG. 2 and is normally of reduced height having a height h , as of $\frac{1}{3}$ of its width, where the height h and the width w are shown in FIG. 1. The transformer is indicated at 12 in FIG. 2 and it may comprise a uniform taper in height of the guide or, as an alternative, one or more steps in the height of the guide, as shown in FIG. 2, for effecting an impedance match between the low height guide 11 and the normal height guide 5. Such impedance transform-

ers 12 utilize additional space and are relatively costly to manufacture.

Referring now to FIG. 3 there is shown a composite microwave window and waveguide transformer 15 incorporating features of the present invention. The structure of the composite microwave window and waveguide transformer 15 is substantially the same as that previously described with regard to FIG. 1 and 2 with the exception that the input waveguide 5, which is connected to the central waveguide section 2, is of reduced height. More particularly the input waveguide 5 is of rectangular cross section having a height h approximately $\frac{1}{3}$ of its width w . The coupling hole 7 in the end wall 4 is of rectangular cross section having a cross section of the same dimensions as the inside cross section of the low impedance input waveguide 5.

The microwave window member 9 is sealed across the center cylindrical waveguide section 2 at a point which is displaced from the midpoint toward the waveguide of reduced height, namely, waveguide 5. The window member 9 is displaced by an amount to produce a broadband match such that the composite microwave window with the displaced window member 9 forms a composite microwave window and impedance transformer. In a typical example, the center of the microwave window 9 is displaced from the midpoint of the length of cylindrical waveguide 2 by approximately 17% of the length of the waveguide 2. Waveguide 2 has a length 1 which is approximately 85% of $\frac{1}{2}$ of a free space wavelength. The window 9 is dimensioned such that the distance d between the regions just inside the connecting waveguides 5 and 6, at the abrupt transitions 7 and 8, is approximately $\frac{1}{2}$ of an electrical wavelength when taking into effect the loading produced by the window 9 and the fringing field regions at the abrupt transitions, such fringing field regions extending slightly into the adjacent waveguide sections 5 and 6. Alternatively, d could be $n/2$ electrical wavelengths where n is any odd integer.

In a typical example at s band, input waveguide 5 had a width of 2.84 inches and a height which was $\frac{1}{3}$ of the normal height, namely 0.892 inch. The output guide 6 had a width of 2.84 inches and a height of 1.34 inches. The cylindrical waveguide section 2 had a diameter of 9.03 centimeters and a length 1 of 3.85 centimeters. The window member 9 was made of alumina ceramic having a thickness of 0.36 centimeters.

The composite microwave window and waveguide transformer of the aforesaid dimensions had a passband characteristic as shown in FIG. 4, wherein the passband was approximately 13% or 400 MHz between VSWR points of 1.1 centered at a frequency of approximately 2.8 GHz. The composite microwave window and transformer 15 passed 4 MW peak and greater than 8 KW average power. The output waveguide 6 and that portion of the central waveguide section 2 in gas communication therewith was pressurized with SF₆ at a pressure of approximately 25 psi gauge. The input

waveguide 5 was connected via flange 17 to the output waveguide of the microwave tube not shown, and the output waveguide 6 was connected to conventional standard size S- band waveguide via waveguide flange 18.

What is claimed is:

1. In a high frequency gas tight wave permeable window assembly dimensioned for passing wave energy therethrough over a certain passband of frequencies, a first tubular waveguide member having a first height, second and third tubular waveguide members having waveguide heights substantially less than the height of said first guide, centrally apertured end walls of said first waveguide member forming abrupt waveguide transitions for connecting said second and third waveguide members to said first waveguide member substantially at the ends of the said first waveguide member, a gas tight wave permeable window member disposed transversely of and within said first waveguide member, the thickness of said wave permeable window member being substantially less than $\frac{1}{2}$ of an electrical wavelength at the center frequency of the passband of the wave permeable window assembly, and the length of said first waveguide member plus the fringing field regions extending into the adjacent second and third waveguides at said abrupt transitions, and with said wave permeable window in place, being approximately $n/2$ electrical wavelengths long at the center frequency of the certain passband of said window assembly, where n can have any odd integer value, said second waveguide member having a substantially uniform lower height than said third waveguide member, and said wave permeable window member being substantially displaced from the midlength position in said first waveguide toward the end thereof connecting to said second waveguide, whereby a relatively broadband composite microwave window and waveguide transformer is obtained.

2. The apparatus of claim 1 wherein said first waveguide is of circular cross section, said second and third waveguides are of rectangular cross section, and said apertures in said end walls of said first waveguide are each rectangular.

3. The apparatus of claim 2 wherein said second waveguide has a height approximately $\frac{1}{3}$ of its width, and said third waveguide has a height which is approximately $\frac{1}{2}$ its width.

4. The apparatus of claim 3 wherein said window is displaced by approximately 17% of the length of said first waveguide from the midlength position in said first waveguide.

5. The apparatus of claim 4 wherein the length of said first waveguide in between said end walls is approximately 85% of a free space wavelength at the center of the passband of the composite window and transformer.
